UNITED STATES PATENT OFFICE

RALPH H. GILBERT, OF NEW YORK, N. Y.

WARNING SIGNAL FOR AUTOMOBILES

Application filed March 31, 1926. Serial No. 98,675.

This invention relates to warning signals for automobiles, having for its principal object to provide signal means for automatically notifying drivers of other vehicles when the vehicle is being rapidly retarded as by the application of the brake, in combination with means necessarily made effective before the brake is applied for giving them timely preliminary warning prior to operation of the 10 brake.

To this end, it is a feature of the invention that provision is made of means to exhibit a "Slow" or other warning signal whenever the foot of the driver is withdrawn from the foot 15 accelerator, and to exhibit a "Stop" or other danger signal as soon as the brake is applied. Since the service brake and the foot accelerator are arranged for operation by the same 20 foot of the driver, the application of the brake requires that the foot be first withdrawn from the accelerator, so that the signals are invariably displayed in proper sequence.

The invention is not, however, limited to use in conjunction with a foot accelerator, as 25 the preliminary signal may be operated advantageously from the hand feed lever in automobiles in which no foot accelerator is provided.

Other objects and advantages will herein- 30 after appear.

In the drawing there is shown diagrammatically the electrical apparatus and the operating means therefor whereby the novel signal mechanism is controlled.

The automobile battery 1 is connected through a conductor 2, manually operable switch 3, and conductor 4, with a switch contact member 5 which is normally in the position shown in the drawing and is mechanically connected by link 6 with the service brake 7. In its normal position the contact member 5 engages a contact 8, which is connected through conductor 9 with a movable contact member 10. The contact member 10 is controlled by the foot accelerator 11, through a connection 12, the contact member 10 being pressed into engagement with the cooperating contact member 13 when the foot accelerator is released, and being withdrawn from engagement with the contact member 13 by

the foot accelerator, when the foot is depressed. Contact member 13 is connected through a conductor 14, with a warning light signal 15 marked "Slow", which is connected to ground through a conductor 16.

There is also arranged for cooperation with the contact switch 5, a contact member 17, into engagement with which the switch member 5 is moved by depression of the foot brake 7 to retard the vehicle. Contact member 17 is connected through a conductor 18, with a danger light signal 19 marked "Stop", that is grounded through the conductor 16. The circuit is completed to the battery through a conductor 20 which grounds one side of the battery. The foot accelerator and the service brake are arranged for alternative operation by a single foot of the driver, so that one or the other, but not both, may be depressed at any given moment. When the vehicle is running and fuel is being fed by the accelerator, the contact member 5 is normally in engagement with contact 8, but the contact member 10 is held out of engagement with contact member 13 by the accelerator. Under these circumstances no current can flow through either the "Slow" or the "Stop" signal, the circuit to the former being open between the contacts 10 and 13, and the circuit to the latter being open between the contacts 5 and 17. When the operator has occasion to stop or retard the vehicle, he first withdraws his foot from the foot accelerator. This immediately causes the contact member 10 to be swung into engagement with contact member 13, completing the circuit through the "Slow" signal, which thus serves as a warning to following motorists that the foot feed is no longer being used, and that the brake is apt to be applied. The operator then steps on the foot brake 7, retarding the vehicle. The foot brake swings the switch contact member 5 out of engagement with the contact member 8, opening the circuit to the "Slow" signal and extinguishing it, and into engagement with contact member 17, closing the circuit to the "Stop" signal, and lighting it.

From the foregoing description, it will be seen that provision is made of a brake-con-

trolled "Stop" signal indicating danger, and of a "Slow" signal, serving as a warning to be operated in advance of the "Stop" signal, the controls of the two signals being so arranged 5 and so related that the normal mechanical operation of the vehicle will cause the signals invariably to appear in the proper sequence.

It frequently happens that the operator of 10 a vehicle, having retarded it by application of the brake and released the brake, will allow it to drift forward for a period before resuming the feeding of fuel by the accelerator. During this period the "Slow" signal will again be effective and will remain effective until the 15 driver has decided again to proceed rapidly, at which time the depression of the foot accelerator will extinguish the "Slow" signal.

The manually operable switch 3 for rendering the described signal mechanism operative or inoperative at will is preferably 20 operated by the member that operates the ignition switch, this member being usually mounted on the dashboard of the machine. By utilizing this means to operate the signal 25 the need for providing a separate operating means for the switch 3 is obviated, and provision is made for assuring that the signal means will be effective whenever the car is in operation, and that it will not be 30 left lighted when the car is parked or put away.

In case the "Slow" signal is arranged for 35 operation by the hand feed lever, as it would be on a Ford car, the "Slow" and "Stop" signals will not of necessity be operated in the sequence named. They will, nevertheless, 40 cooperate to impart useful information to the drivers of other vehicles. Thus, if the brake is applied without moving the hand lever, the "Stop" signal will be operated at once. If the feeding of fuel is reduced 45 without applying the brake, the "Slow" signal will be operated. If the feeding of fuel is first reduced, and the brake is then applied, the "Slow" signal will first be operated and the "Stop" signal will then be operated and, due to the circuit arrangement 50 described, will extinguish the "Slow" signal.

50 Variations may be resorted to within the scope of the invention and parts of the improvements may be used without others.

What I claim is:

1. In a motor vehicle, the combination with 55 a foot accelerator and a foot brake, arranged for alternative operation by the same foot, of a warning signal, means for operating said warning signal made effective by the release of the foot accelerator, a danger signal 60 and means for operating said danger signal made effective by the application of the foot brake.

2. In a motor vehicle, the combination with 65 a foot accelerator and a foot brake, arranged for alternative operation by the same

foot, of an electrically operated warning signal, an operating circuit therefor including a switch member movable to circuit closing position by the release of the foot accelerator, an electrically operated danger signal, 70 an operating circuit therefor, and means operated by the application of the foot brake, to break the circuit to the warning signal and to close the circuit to the danger signal.

3. In a motor vehicle, in combination, a 75 brake, means for controlling the feeding of fuel to the motor, a pair of signals, means operated by the application of the brake and by the release of the fuel feed control, respectively to operate the respective signals, 80 to give successive indications that the vehicle is to be retarded, and means operated by application of the brake to disable the signal operated by the fuel feed control.

In testimony whereof I have affixed my 85 signature to this specification.

RALPH H. GILBERT.
